(57) **CLAIM**

The ornamental design for a solar cell module, as shown and described.

DESCRIPTION

FIG. 1 is a front view of a solar cell module showing the claimed design;

FIG. 2 is a rear view thereof;

FIG. 3 is a top plan view thereof, the bottom plan view being the same;

FIG. 4 is a right side view thereof, the left side view being the same;

FIG. 5 is an enlarged view of the portion between 5-5 and 5'-5' in FIG. 1;

FIG. 6 is an enlarged cross-sectional view taken along line 6-6 in FIG. 1; and,

FIG. 7 is an enlarged cross-sectional view taken along line 7-7' in FIG. 5, within the portion 7-7 in FIG. 5.

In the drawings, the broken lines show portions of the solar cell module that form no part of the claimed design.
